UNITED STATES PATENT OFFICE.

EDWARD HOLBROOK, OF NEW YORK, N. Y.

DESIGN FOR A HANDLE FOR SPOONS, &c.

SPECIFICATION forming part of Design No. 27,849, dated November 16, 1897.

Application filed October 4, 1897. Serial No. 654,095. Term of patent 7 years.

To all whom it may concern:

Be it known that I, EDWARD HOLBROOK, a citizen of the United States, residing at New York, in the county of New York and State of New York, have invented and produced a new and original Design for a Handle for Spoons, Forks, or Similar Articles; and I hereby declare that the following is a full, clear, and exact description of the same, reference being had to the accompanying drawings, forming part thereof.

Figure 1 is a view of the obverse side of a spoon provided with a handle showing my design. The tines of a fork are indicated in broken lines. Fig. 2 is a view of the reverse side of the same.

The leading feature of my design consists in the peculiar and novel arrangement of the representations of stems, leaves, spikes, and blossoms of meadow-grasses for the ornamentation of the handle.

In the drawings, A indicates the bowl of the spoon, B the stem of the handle, and C the blade of the handle. On the obverse side the raised stems 3 3 extend along the edges of the handle. At the lower end, between the stems, the representation of short-leaved bunch-grass 4 fills the space between the representation of the stalks or stems 3 3. The leaves 5 5 extend diagonally across the handle, and above these leaves the representation of the blossoms and leaves of white clover 6 fill the space between the stems. A bunch of leaves 7 extends across the handle, and above these 35 a bunch of leaves 8 extends diagonally across the handle and, extending upward, curves inward, inclosing the floral spike 9, representing the flowering spike of the grass known

as the "crested dogstail." From the upper ends of the curved leaves 8 extend the 40 branches 10, representing the flowers of the meadow-grass known as the "rough cocksfoot." The leaves 11 11 extend diagonally on each side of the panel 12 and terminate in the end ornament 13, representing the blossoms 45 and leaves of white clover.

On the reverse side of the handle, Fig. 2, the stems 3 3 extend from the ornament 4, representing leaves and blossoms of grasses. The stems 3 3 extend along the edges of the 50 handle, and the leaves extend from the stems inward and upward, giving to this side of the handle a lighter and more open appearance. On the stem of the handle the spikes 14 14, resembling the timothy or meadow catstail, 55 extend from the opposite stems 3 3. A bunch 10 of the flowers of the meadow-grass rough cocksfoot extends across the blade of the handle below the panel 12, and a bunch of blossoms and leaves 13, resembling the white 60 clover, forms the end ornament of the handle. The whole presents to the eye the appearance of meadow-grasses, flowers, leaves, and spikes in relief.

Having thus described my invention, what 65 I claim as new, and desire to secure by Letters Patent, is—

The design for a handle for a spoon, fork or similar article herein shown and described.

In witness whereof I have hereunto set my 70 hand.

EDWARD HOLBROOK.
